COMBINATION SINK AND DRINKING FOUNTAIN

Joseph J. Salemi, Chicago, Ill., assignor to Elkay Manufacturing Company, Chicago, Ill., a corporation of Illinois

Application February 12, 1958, Serial No. 49,618

Term of patent 14 years

(Cl. D4—2)

Fig. 1

Fig. 2

Fig. 3

Figure 1 is a perspective view of a combination sink and drinking fountain, embodying my new design;

Figure 2 is a top plan view of the combination sink and drinking fountain of Fig. 1; and

Figure 3 is a front elevational view of the combination sink and drinking fountain of Fig. 1.

The dominant features of the design reside in the solid line portions.

I claim:

The ornamental design for a combination sink and drinking fountain, as shown and described.
